UNITED STATES PATENT OFFICE.

PAUL J. McCULLOUGH, OF ST. LOUIS, MISSOURI, ASSIGNOR TO SCULLIN STEEL CO., OF ST. LOUIS, MISSOURI, A CORPORATION OF DELAWARE.

JOURNAL-BOX-SECURING MEANS.

Application filed January 17, 1927. Serial No. 161,576.

The present invention relates to journal box securing means.

The present invention relates to journal boxes which are separable from the side frames and has reference to the construction of such boxes and the securing means therefor.

An object of the present invention is to provide a construction of side frame and separable journal box which will hold the journal box rigidly in position but which will permit the separation of said journal box from said side frame with a single straight line movement upon the removal of a certain part of parts.

A further object is to provide an improved securing means for a separable journal box which cooperates with the parts of journal boxes as at present provided and which permits removal of the journal box in a simple straight line movement of said journal box relative to the side frame.

A further object is to provide means for securing a journal box to a side frame which will cooperate with the hinge construction usually provided for the lid of the journal box and which will permit separation of said journal box from its side frame when said lid or parts of the hinge of said lid are removed.

Referring to the drawings—

Figure 1 is a top plan view of part of a side frame having a separable journal box applied thereto, which frame and journal box employ the principles of the present invention;

Figure 2 is a side view of the structure shown in Figure 1, parts being broken away to better illustrate the construction;

Figure 3 is a view taken along the plane indicated by the arrows 3—3 of Figure 2;

Figure 4 is an end view of the structure shown in Figures 1 and 2;

Figure 5 is a view similar to Figure 1, but showing a slight modification;

Figure 6 is a view similar to Figure 3, but illustrating the modification embodied in Figure 5;

Figure 7 is a view similar to Figures 1 and 5, but showing a further modification;

Figure 8 is a view similar to Figures 3 and 6, but illustrating the modification embodied in Figure 7;

Figures 9 and 10 are similar to Figures 7

and 8, respectively, but showing a modified construction;

Figures 11 and 12 are views similar to Figures 9 and 10, but showing a still further modification; and

Figure 13 is a view similar to Figure 12, but showing a slight modification.

Referring first to Figures 1, 2, 3 and 4, the numeral 10 indicates a side frame having jaws 10^a and 10^b, and the numeral 11 indicates a journal box for supporting said side frame between said jaws. Said side frame is provided with the flanges 12 and 13 on the two sides thereof, which flanges are adapted to be positioned between the gibs 14 and 15 formed upon the upper side of the journal box 11. With the flanges 12 and 13 of said side frame disposed between said gibs 14 and 15, movement of the journal box transversely of the side frame is effectually prevented. It will be understood, of course, that an axle (not shown) is disposed within the journal box 11, which journal box is provided with the usual brass and wedge which carry the journal box. The flanges 12 and 13 upon the side frame and the gibs 14 and 15 extend along three sides of the journal box 11, engaging the flanges on the side frame 10, whereby tilting or rotating of the journal box relative to the axle and to the side frame is effectually prevented.

The journal box 11 is provided with the usual swinging lid 16, which lid forms a closure for one end of said journal box 11. Said lid is swingingly mounted upon the pin 17, the upper portion of said box being provided with lugs 18—18 and the upper extremity of said lid 16 being provided with lugs 19—19, said lugs 18—18 and 19—19 having registering apertures for receiving said pin 17. The pin 17 may be provided with cotters or other devices for removably holding said pin in position. Said frame 10 is provided with lateral extensions 20—20, the extremities of which are adapted to underlie the pin 17. As shown in Figures 1 to 4 of the drawings, the extremity of the lateral extensions 20—20 are disposed below the lugs 19—19 of the lid 16, said lugs 19—19 being formed to clear the extremities of said lateral extensions 20—20, whereby no interference is had with the movement of said lid. Between the lugs 20—20, the journal box 11 is formed with an angular portion 21

adapted to have cooperation with the spring 22 secured to the lid 16. Said spring 22 will selectively hold the lid 16 in either open or closed position, by reason of the engagement of the spring 22 upon the upper or lower side of the angular portion 21. In the form of the invention illustrated in Figures 1 to 4, inclusive, the gib 14 upon the journal box 11 is cut away to allow for the lateral extensions 20-20 on the side frame 10.

Figures 5 and 6 illustrate a slightly modified construction, in which two lugs 23-23 upon the upper portion of the journal box 15 embrace a single lug 24 formed upon the extremity of a lateral extension 25 of the side frame 10. The lid 16, a portion of which is shown in Figure 5 but which is omitted from Figure 6, has the lugs 19, 20 which embrace the lugs 23-23 of the journal box 11. The pin 17 holds the extremity 24 of the side frame, the lugs 23-23 of the journal box and the lugs 19-19 of the lid 16 in aligned position.

Figures 7 and 8 illustrate another modification, in which a single lateral extension 25 is provided on the side frame 10, which lateral extension 25 underlies and engages the pin 17 between the lugs 23-23 of the journal box 11.

Figures 9 and 10 illustrate a modification wherein the holding effect of the hinge construction of the lid 16 is supplemented by a pin 26, which is adapted to be disposed within registering recesses in the lateral extensions 27 on the side frame 10 and bosses 28 on the top of the journal box 11.

Figures 11 and 12 illustrate a construction very similar to the construction in Figures 9 and 10, except that a single lateral extension 29 is provided on the side frame 11 which has an aperture adapted to register with apertures in the bosses 30-30 upon the top of the journal box 11. A pin (not shown) similar to the pin 26 is adapted to hold the journal box 11 in position with respect to the side frame 10.

All of the preceding figures show constructions in which the gib 14 is cut away to provide space for the lateral extension or extensions upon the side frame 10. Figure 13 shows a construction in which the gib 14 is continuous over the top of the journal box, the lateral extension 31 being cored out 55 to clear said gib 14.

Many modifications will occur to those skilled in the art. It is intended to cover all such modifications that fall within the scope of the appended claims.

What is claimed is—

1. In combination, a side frame, a separable journal box cooperatively associated therewith, said side frame having a pair of jaws, said journal box having a pair of gibs

for receiving said jaws and for preventing a rotative movement between said side frame and said journal box, a swinging closure for said journal box, and a hinge pin for said closure member, said pin having engagement with said side frame and said journal box 70 for preventing relative vertical movement between said side frame and said journal box.

2. In combination, a side frame, a separable journal box cooperatively associated therewith, said journal box being provided 75 with a closure member and means responsive to said closure member for preventing relative vertical movement between said journal box and said side frame, said journal box being provided with abutment means 80 operating with said side frame to prevent tilting movement between said journal box and said side frame.

3. In combination, a side frame, a journal box, removable closure means at one end 85 of said journal box, said side frame being provided with a lateral extension adapted to underlie a portion of said closure means to prevent relative vertical movement between said box and said frame, said journal box 90 having abutment portions cooperating with said side frame to prevent relative movement therebetween except in a straight line movement.

4. In combination, a side frame and a removable journal box, said box being provided at one of its extremities with movable closure means, said frame being provided with a portion cooperating with said movable closure means to prevent relative movement between said box and said frame, said journal box having a pair of gibs for embracing the two sides of the jaws of said side frame to prevent relative tilting movement between said journal box and said side 100 frame.

5. In combination, a side frame and a separable journal box, said journal box having closure means, said side frame having a lateral extension for engaging said closure 110 means to prevent vertical movement therebetween, said side frame and journal box having cooperating abutting portions to prevent a tilting movement of said journal box relative to said side frame.

6. In combination, a side frame and a separable journal box, said side frame having jaws for embracing said journal box, a pin disposed in registering apertures in said side frame and journal box to prevent relative 120 vertical movement therebetween, said side frame and journal box having cooperating abutting portions to prevent tilting movement of said journal box relative to said side frame.

Signed at St. Louis, Missouri, this 13th day of January, 1927.

PAUL J. McCULLOUGH.
